Primary Examiner — Cynthia Ramirez*Assistant Examiner* — Laura H Yu(57) **CLAIM**

The ornamental design for a foot dryer, as shown and described.

DESCRIPTION

FIG. 1 is a front elevational view of a foot dryer showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof.

The broken lines in the drawings illustrate portions of the foot dryer which form no part of the claimed design.

1 Claim, 8 Drawing Sheets(56)
